UNITED STATES PATENT OFFICE.

JOHN LOGAN, OF CHICAGO, ILLINOIS.

METHOD OF MANUFACTURING COMPOSITE ROOFING.

Application filed March 13, 1922. Serial No. 543,223.

To all whom it may concern:

Be it known that JOHN LOGAN, a citizen of the United States, and a resident of the city of Chicago, county of Cook, State of Illinois, has invented an Improvement in Methods of Manufacturing Composite Roofing, of which the following is a specification.

This invention relates to the method of manufacturing composite roofing and, among other objects, is intended to provide a method for producing economically and efficiently a roofing material which is water-proof and possesses improved fire resisting qualities, and which forms an efficient heat insulator.

The invention includes, among other things, the application of a metallic sheet or veneer to the surface of composite roofing, such as asphalt-coated felt, preferably as one of the steps in the manufacture of said roofing.

The coating of asphalt, or the like, may be applied to either one or both sides of the felt or other fibrous material, and after having been distributed and gauged to form a layer of uniform thickness over the surface of the felt, has applied thereto the metal veneer to cover, preferably, the exposed portion of the roofing.

The metal veneer may be applied while hot, causing it to adhere more securely to the coated-felt and, if desired, may be provided with perforations arranged in any desired design, whereby the asphalt coating may be pressed into and exposed to view through said perforations.

The invention may be best understood by reference to an illustrative method embodying the invention, and illustrated, somewhat diagrammatically, in the drawings.

Referring to said drawings:

Fig. 1 is a diagrammatic view illustrating one mode of manufacture of the roofing.

Fig. 2 is a perspective view of a fragment of the roofing representing a strip constructed in accordance with the improved method.

Referring to the drawings, and particularly to Fig. 1 thereof in which is illustrated one method by which the desired results may be accomplished, a sheet 5 of fibrous material such as cheap rag felt, or the like, is supplied from a roll 6 and passed through a bath 7 of impregnating compound such, for example, as light asphalt.

The said asphalt or other compound is preferably of such consistency and temperature as to be absorbed readily by the fibrous sheet as the latter passes therethrough.

To remove any excess of impregnating compound which may adhere to the surfaces of the sheet 5 as it emerges from the bath, the sheet is passed between a pair of squeeze rolls 8 and 9, one of which may be adjustable for the purpose of determining the pressure to be exerted upon the sheet 5.

After passing the squeeze rolls, the impregnated fibrous sheet is coated on one or both surfaces with a substantial layer 10 of impervious water-proofing compound, such as heavy asphalt or the like.

This water-proofing compound may be applied to the upper surface of the felt from a hopper 11 and spread thereon by a roller 12 and, if desired, a coating of the compound may be applied to the bottom surface of the felt also, by a roller 13 adapted to convey the compound from a receptacle 14 and deposit it upon the bottom of the sheet.

The rolls 12 and 13 serve to spread the asphalt uniformly over the sheet and to gauge the thickness thereof. One of said rolls may be made adjustable relative to the other to permit of a variation in the thickness of the layers 10.

A relatively thin sheet of metal veneer 15, such as copper or other metal not susceptible to atmospheric conditions is then applied to one of the layers 10, preferably to that portion ordinarily exposed when the same is on a roof or the like, to protect the roofing from sparks, firebrands and the like.

The sheet 15, if desired, may be provided with a series of perforations 16 which may be arranged in straight parallel lines extending transversely of the sheet, as shown in Fig. 2, or may be arranged in any other preferred designs to produce the desired effect when the strip is laid on a roof or the like.

The metal sheet 15 may be applied to the adjacent layer of protecting compound by a roller 17 in a manner to be imbedded therein a distance substantially equal to the thickness of the veneer, thereby bringing its upper surface substantially flush with the uncovered surface of the layer and causing the compound to be pressed into the perforations in a manner to be exposed at 110

the outer surface of the sheet as shown in Fig. 2.

The perforating of the sheet 15 may, if desired, be made a step in the method of manufacture.

The perforations 16 are preferably of greater lineal dimension than the narrow intermediate connecting strips 18, and the exposure of the compound therethrough 10 presents the appearance of a continuous line, suggestive of the space between adjacent edges of ordinary shingles when the overlapping strips are laid on a roof or the like.

If desired, the roller 17 may be so positioned as to cause the compound to be pressed through the perforations and beyond the outer surface of the sheet 15 where it may be pressed or permitted to cover the connecting strips 18, thereby actually forming a continuous line of compound at the surface of said sheet.

The strip 15 may be of copper or similar material and may be supplied from a roll 19, passed over a heated roller 20 and beneath 25 the roller 17 where it is applied to the roofing.

By heating the veneer as it passes over the roller 20 and pressing it firmly upon the coat of impervious compound 10 will cause 30 it to adhere securely thereto.

To prevent the asphalt or other compound from adhering to the roller 17 where the latter engages the said compound as it emerges from the perforations 16, there may be provided a hopper or other receptacle 21 containing flake mica, soapstone or the like and adapted to deposit the same on the surface 35 of said roller.

Obviously, the metal strip 15, if desired, 40 may be corrugated, embossed or otherwise impressed with decorative designs, or may be oxidized or otherwise treated to produce the desired appearance.

The roofing embodying this invention 45 may be made in long sheets to be handled in rolls as in the case of some prepared roofing at present in use or may be cut to form individual shingles, or into shingle strips of any desired width by the cutters 22.

Suitable supports may be provided for the 50 proper handling of the roofing through the process of its manufacture.

Obviously, the present invention is not 55 limited to the particular arrangement shown, but may be variously modified. Moreover, it is not indispensable that all the features of the invention be used conjointly, as they may be used to advantage in va-

riously different combinations and sub-combinations.

Having thus described my invention, I claim:

1. A method for making composite roofing which includes: impregnating a sheet of fibrous material with a solution of light asphalt; removing the excess asphalt from said sheet; applying layers of heavy asphalt to opposite sides of said impregnated sheet; gauging the thickness of said layers; applying a heated copper veneer to one of said layers; and imbedding the veneer therein. 60

2. A method for making composite roofing which includes: impregnating a sheet of fibrous material with a preserving solution; removing excess solution from said sheet; applying layers of impervious water-proofing compound to opposite sides of said sheet; gauging the thickness of said layers; heating a thin metal veneer and imbedding the same into one of said layers. 75

3. A method for making composite roofing which includes: impregnating a sheet of fibrous material with a preserving solution; applying one or more layers of impervious water-proofing compound to said sheet; gauging the thickness of said layers; heating a veneer of thin metal and applying the same to one of said layers. 80

4. A method for making composite roofing which includes: impregnating a sheet of fibrous material with a preserving solution, applying to said sheet one or more layers of impervious water-proofing compound gauging the thickness of said layers; applying a veneer of heated metal to one of said layers 90 and cutting the roofing so formed into desired widths. 95

5. A method of making composite roofing of the type described which comprises, coating a sheet of fibrous material with a layer of heavy asphalt and while in softened condition applying thereto a relatively thin perforated sheet of copper for substantially covering the area of the roofing to be exposed. 100

6. The method of making composite roofing which comprises, coating a sheet of material with a layer of impervious adhesive water-proofing compound, and applying thereto under pressure a surface sheet of thin metal having spaced groups of small perforations. 105

In testimony whereof, I have signed my name to this specification.

JOHN LOGAN.
